Primary Examiner — Michelle E. Wilson*Assistant Examiner* — Clese Moore, Jr.(74) *Attorney, Agent, or Firm* — IPTechLaw(57) **CLAIM**

The ornamental design for a bicycle stand, as shown and described.

DESCRIPTION

FIG. 1 is a front perspective view of a bicycle stand; FIG. 2 is a front view thereof, the rear view thereof being a mirror image;

FIG. 3 is a left side view thereof, the right side view being a mirror image;

FIG. 4 is a top view thereof; and,

FIG. 5 is a bottom view thereof.

All broken lines represent unclaimed features of the article to which the design is applied and form no part of the claimed design.
